UNITED STATES PATENT OFFICE.

JAMES J. THOMAS, OF WHITING, IOWA.

SHOE-LACER.

1,083,775.

Specification of Letters Patent.

Patented Jan. 6, 1914.

Application filed October 4, 1911. Serial No. 652,683.

To all whom it may concern:

Be it known that I, JAMES J. THOMAS, a citizen of the United States, residing at Whiting, in the county of Monona and State 5 of Iowa, have invented new and useful Improvements in Shoe-Lacers, of which the following is a specification.

The invention relates to shoe fasteners, and more particularly to improvements in 10 Letters-Patent No. 991,251, issued to me May 2, 1911.

The primary object of the invention is the provision of a lacer in which the upper of a shoe may be properly adjusted, so as to 15 snugly fit about the ankle of a wearer, and that will permit the ready and quick lacing and unlacing of the shoe, without the use of a shoe string or other lacing of a similar type.

20 Another object of the invention is the provision of a device of this character which may be adjusted to various styles of shoes, whereby the same may be readily and quickly fastened or unfastened, the device being 25 readily adjustable, so as to permit a shoe to properly fit a wearer.

A still further object of the invention is the provision of a lacer of this character which is simple in construction, efficient in 30 its purpose, and inexpensive in manufacture.

With these and other objects in view, the invention consists in the construction, combination and arrangement of parts, as will be hereinafter more fully described, illustrated in the accompanying drawings, and 35 pointed out in the claim hereunto appended.

In the drawings: Figure 1 is a perspective view of a shoe of the ordinary construction, with the lacer attached thereto constructed 40 in accordance with the invention, the shoe upper being partly laced. Fig. 2 is an enlarged longitudinal sectional view through the lacer and adjacent parts of the shoe upper. Fig. 3 is a sectional view on the line 45 3-3 of Fig. 2. Fig. 4 is a perspective view of one of the eye members detached from the shoe upper. Fig. 5 is a perspective view of the rider member of the device.

Similar reference characters indicate 50 corresponding parts throughout the several views of the drawings.

Referring to the drawings by numerals, the shoe is of the ordinary well-known construction, comprising a body 5 having an 55 upper 6, the latter being provided with the usual vent at the front of the shoe, and at

opposite sides of which are arranged the ordinary flaps 7. Connected with the shoe body 5 and adapted to underlie the flaps 7 is the usual tongue 8, the flaps 7 being reinforced at their inner faces by means of leather strips 9, which are stitched or otherwise secured thereto in any suitable manner. These reinforcing strips 9 are common in shoes ordinarily used. Carried by the 60 flaps 7 and the reinforcing strips 9 is the shoe fastening or lacing device, presently described.

The shoe fastening or lacing device comprises a series of hollow tubular members 70 10 and 11, respectively, the members 11 being provided with downturned hooks 12 which are adapted to detachably engage in openings or slots 13 formed in the members 10. The members 10 and 11 are each formed 75 with central laterally extending wings 14 provided at their free ends with eyes 15, and through these eyes 15 is trained or threaded a string 16, the same being also threaded through eye members 17 fixed to the flaps 80 7 and reinforcing strips 9, so as to project beyond the edges thereof in spaced relation to each other.

By reference to Fig. 3 of the drawings it will be noted that the wings 14 are integrally formed with the tubular members 10 and 11, and comprise a strap which is approximately centrally offset at an angle from each of said members. The strap is bent to provide the eye 15, and is from 85 thence continued inwardly toward the tubular member and passed through a suitable opening in the outer side of said tubular member. The portion entering the opening 90 is bent at an angle to engage with the inner 95 face of said tubular member and to sustain its longitudinal portions or arms in engagement with each other.

The members 10 and 11 are formed at 100 opposite ends with links 18, loosely engaging each other, so as to permit the flexing of the said members 10 and 11 when opening and closing the vent in the shoe upper, it being seen that the said members 10 and 11 are arranged in rows at opposite sides of 105 the vent, while the lowermost members 10 and 11 of the rows, at the lower end of the vent, have their links 18 pivoted or otherwise connected to a terminal plate 19 which is permanently arranged at the lower or 110 closed end of the vent, and is formed with terminal eyes 20, through which is threaded

the string 16. Thus, it will be seen that upon loosening the string 16, the members 10 and 11 will be permitted to be spaced from the flaps 7, thereby increasing the size 5 of the shoe upper, and upon tightening the string, the said shoe upper will be decreased in size, so that in this manner it will properly fit the instep of the wearer of the shoe.

Mounted for sliding engagement with the 10 members 10 and 11 is a rider member, comprising diverging sleeve portions 21 which are slotted, as at 22, in their concave sides, for the free travel of the said rider upon the members 10 and 11, the slits 22 in the 15 rider being designed to receive the wings 14 and allow the sleeve portions 21 to pass to either side of the same. This rider, when traversing the members 10 and 11 toward the upper edge of the upper 6 of the shoe, causes the members 10 and 11 to approach each other and bring the hooks 12 on the members 11 into engagement in the openings 13 in the members 10, thereby locking the members together for the closing and 20 fastening of the vent in the shoe upper.

Each of the eye members 17 carried by the shoe upper 6 comprises a single strip of metal 23, from one end of which is cut a bendable locking tongue or spur 24 which 25

is adapted to engage in an opening 25 in 30 the opposite end thereof, so that upon bending the strip 23 into substantially U-shape, whereby the ends thereof will lie at opposite sides of the upper 6 against the outer face of the flap 7 and the outer face of the 35 reinforcing strip 9, a blow from a suitable tool will force the spur 26 through the opening 25 and clench the said spur, thereby securing the eye member 17 to the shoe upper, as will be obvious. 40

What is claimed is:

In a device for the purpose set forth, tubular interlocking members, each of said members having its outer side provided with an integrally formed longitudinally extending wing, each of said wings being centrally bent to provide an eye, the wing beyond the eye being projected through an opening in the side of the tubular member, and an extremity of the wing being bent against the 50 inner face of said tubular member. 45

In testimony whereof I affix my signature in presence of two witnesses.

JAMES J. THOMAS.
